UNITED STATES PATENT OFFICE.

FREDRICK H. HAMAN, OF WAPAKONETA, OHIO.

CHURN.

SPECIFICATION forming part of Letters Patent No. 410,888, dated September 10, 1889.

Application filed May 29, 1889. Serial No. 312,592. (No model.)

To all whom it may concern:

Be it known that I, FREDRICK H. HAMAN, a citizen of the United States, and a resident of Wapakoneta, in the county of Auglaize and State of Ohio, have invented certain new and useful Improvements in Churns; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a vertical transverse section. Fig. 2 is a plan view. Fig. 3 is a horizontal sectional view. Figs. 4 and 5 are detail views.

This invention relates to churns; and it 20 consists in the construction and novel combination of parts, as hereinafter described, and pointed out in the claim.

In the accompanying drawings, the letter A designates the body of a barrel-churn suspended in suitable bearings on a frame B by hangers C and D.

E indicates an annular ring for the reception of the churn-head, said ring having four shouldered hook-lugs H thereon, arranged at 30 equidistant points, and under which project the ends of arms L through staples I of the churn-head K when the lid is in place. The arms L have at their inner ends hook-extensions b, projecting from shoulders a, in order 35 that they may be clamped around the pivots l of their bearings c on the spider N. The spider N, carrying the bearings c, is a metal casting having a central opening d, surrounded by a raised rim or shoulder e, to engage stop 40 g on the edge of a cam-lever O, adapted to fasten the parts together. The cam-lever is eccentrically pivoted in the bifurcated or slotted upper end of a threaded rod P, which 45 passes through the openings d of the spider and is screwed into an internally-threaded casting R, bolted at i to the center of the churn-head. After the threaded rod P has been screwed into the casting R a sufficient 50 distance the cam-lever O is depressed until the inner shoulder of the angular stop g engages at any point against the raised rim or shoulder of the said casting. When the lid

is placed on the churn and the end of the cam-lever O is depressed, the outer ends of the four oblique arms L are projected under the 55 shoulders D' of the hook-lugs H by the pressure of the cam on the spider, and the lid or cover is locked firmly in place.

It will be observed that the head of the cam-lever is pivoted diagonally opposite the stop 60 g in order that after the said cam passes the center the said stop shall prevent its further passage and retain it in position at any point around the raised rim of the central opening 65 of the spider.

The hangers C and D of the churn each consist of a casting having centrally-perforated base A', provided on its inner surface with projections or spurs c', and a hollow journal d', projecting from the base. The hangers are 70 secured to the side of the churn on opposite sides by bolts e', passing through the middle portions of the staves and through the hollow journal, the said bolt being held in place by a nut g on its outer end. The spurs c' of 75 the base engage the face of the outer surface of the staves and serve to hold the hangers firm when bolted in position. One of the hangers D is extended outward and usually tapering toward its end to receive a handle 80 or crank S, which is secured with the hangers to the side of the churn by a bolt and nut in a manner similar to that described in connection with the hanger C of the opposite side. The tapering end of the hanger or journal C is flattened on one side at h to engage 85 a corresponding flat surface k in the opening l of the crank to prevent the latter from turning on its bearing.

The body of the churn A is constructed of 90 staves joined together at their meeting edges by V-shaped tongues t, rising from radial shoulders t', adapted to fit in corresponding V-shaped grooves f' of the adjoining stave, having radially-beveled edges i' on each side 95 of the groove to engage the inwardly-inclined shoulders of the tongue t.

The object of the construction is to provide in each stave a continuously-penetrating tongue to engage the corresponding groove 100 in the adjoining stave, acting when the surrounding hoops are being driven over the barrel to bring the staves neatly together, and serving to form a closer joint than can be ob-

tained by the ordinary rectangular tongue and groove.

The frame in which the churn is hung consists of the opposite vertical uprights A'', secured at their lower ends by a tenon-and-mortise joint to the base-pieces B'', respectively, the upper ends of the uprights furnishing bearings for the hangers of the churn. The mortises are supplied with glue, in which the tenons are sunk. The sides of the frame are mortised half-way through their thickness at h' to receive the shouldered ends of the connecting-rounds k'. The ends of the rounds are also sunk in glue, and, being prevented from passing through the sides by their shoulders, the face walls of the mortises preserve the frame at these points from contact with water or moisture, which would otherwise render the joints defective. The sides of the frame are further strengthened by bolt-rods

of metal T, passing through from side to side at the base of the frame and parallel and adjacent to the rounds of the frame.

Having described this invention, what I claim, and desire to secure by Letters Patent, is—

In a revolving churn, the combination, with the stave and the hollow-journal casting having a base fitting the outer surface of the stave and provided with inner spurs to engage said stave, of the bolt extending outwardly through the stave and journal-casting and provided with a nut in its outer end, substantially as specified.

In testimony whereof I affix my signature in presence of two witnesses.

FREDRICK H. HAMAN.
